I claim the ornamental design for a dual view hanging picture frame, as shown and described.

DESCRIPTION

FIG. 1 is an exploded bottom perspective view of a dual view hanging picture frame, showing my new design;

FIG. 2 is a top perspective view thereof;

FIG. 3 is a front elevational view thereof, the rear elevational view being a mirror image thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines showing a photo between two glass panes in FIG. 1 depict environmental matter and form no part of the claimed design.
